ABSTRACT OF THE DISCLOSURE

A plug having a hollow body with inner and outer end members. An open-ended tubular rod is telescopically mounted in the outer member and can be extended from the body to serve as a drill hole marker or can be retracted to a position substantially entirely within the body at which time the bore of the rod registers with an aperture in the inner end member.

This invention relates to a device which serves as both a stopper and an indicator for a drill hole.

When a large number of holes are drilled prior to a blasting operation, it very often happens that a considerable time elapses before the holes are charged with the explosives. During this interval events may occur which will damage the holes or make them difficult, or in some instances, impossible to find. For example, heavy construction equipment moving over the drilled area can very soon make the holes useless for their intended purpose. A heavy rainfall will often erode the side walls of the openings so that they are at least partially blocked. Should there be a fall of snow, the holes are obliterated completely and the whole project is held up until the snow disappears.

The use of plugs to protect such holes has been suggested before but the devices hitherto used are such that they have not been widely accepted by the construction and other industries. Conventional devices are often uneconomical and are otherwise unsatisfactory for a number of reasons. The plugs may be difficult to insert and remove from the holes. Often it will be found that they do not clearly mark the holes. The plugs then form half hidden obstructions which can be a nuisance and sometimes a source of danger to people or vehicles moved over the drilled ground.

The new and improved device of this invention overcomes the above and other disadvantages of the prior art. The present plug is readily inserted by hand and normally is removed without the need for special pulling equipment. Since the device is a press fit only, the holes are not damaged by the plug insertion and removal. The device pinpoints the location of each hole and also makes it possible to discern the drill pattern at a glance.

The invention utilizes a hollow body which is inserted and lightly wedged in the exposed end of the drill hole. A long tubular rod is supported by the body to serve as a marker. One end of the rod can be telescoped into the body to facilitate threading of a fuse cord through the rod whereupon the rod can be raised to its full height so as to be easily located from afar. The body has means for limiting its penetration into the hole and other means to assist in subsequent removal from the hole.

In the drawings,

FIGURE 1 is a vertical section of the invention, part broken away,

FIGURE 2 is a section taken on the line 2—2 of FIGURE 1, and

FIGURE 3 is a section taken on the line 3—3 of FIGURE 1.

2

Referring to the drawings, the preferred embodiment of the device is shown to have a hollow and elongated body which is generally indicated by the numeral 10. The body 10 has a cylindrical side wall 11 and an inner end wall 12. The wall 12 is centrally apertured as at 14. Near the wall 12, the side wall 11 has an inwardly tapered portion 16. A flange 18 is provided on the outer surface of the side wall 11, the flange being disposed in close proximity to the externally threaded outer end 19 of said side wall.

Threadedly engaging the end 19 of the side wall is a cap 21 having a centrally disposed boss 22. An opening 23 is formed in the bossed portion of the cap 19 and preferably this opening is lined with a sleeve 24 of a suitable bearing material. The peripheral edge of the cap is provided with a pair of diametrically opposed lugs 26 which project laterally therefrom.

A tubular rod 30 extends through the opening 23. This marker or locating rod is preferably no more than several inches longer than the body 10, and has a bore 31 and an inner end 32. A stop washer 34 is welded or otherwise secured to the locating rod near the end 32. The rod 30 is slidably mounted in the cap 21 but it will be noted the sleeve 24 offers some resistance to the passage of the rod therethrough. Thus, the locating rod can be raised or lowered with respect to the body 10 and will be held in any selected position by the restraining action of the sleeve 24. When the rod 30 is telescoped or retracted into the body 10, the device is reduced to a length convenient for storage and handling and when said rod is fully extended it is adequately supported by the cap 21.

The body 10 is provided with a protecting sleeve 36 formed of a thin plastic material. The sleeve is shaped to closely fit the side wall 11 and, preferably, to cover at least part of the end wall 12 leaving the aperture 14 clear or unobstructed. Desirably, the length of the plastic sleeve is such that the outer end of said sleeve can be folded outwardly to extend beneath the flange 18.

When an area of rock or the like is to be loosened by blasting, the ground is drilled to provide a large number of suitably spaced holes 40, one of which is shown in FIGURE 1. A corresponding number of the marker plugs are collected at the site, the selected plugs having a body diameter closely conforming to the diameter of the holes being drilled. As each hole is drilled, or at least very shortly thereafter, it is fitted with one of the plugs. The plug is thrust into the upper end of the hole until the flange 18 abuts the surface 41 of the ground adjoining the hole. The rod 30 is then raised until the stop washer 34 bears against the underside of the cap 21, thus providing maximum extension of the locating rod. The hole 40 is then sealed against loose rock and other debris and is distinctly marked for future use.

If below freezing temperatures are likely to be encountered, a plastic sleeve 36 is fitted to each plug before the device is inserted into the ground. The sleeve is slipped over the body 11 of the plug and the outer end of said sleeve is spread out so as to be clamped beneath the flange 18 and the surface 41 of the ground. Should freezing occur, the plastic sleeve 36 prevents the metal plug from sticking to the sides of the hole. The plug can then be removed simply by pulling upwardly on the lugs 26.

When the time comes to load the drill holes with explosives there may be a delay before all the holes are suitably charged and connected up for simultaneous firing. Again, the plugs are useful to seal and mark the charged holes. To load a hole with an explosive charge, the plug is removed and the charge is lowered into the hole by means of the detonating cord 43 which may be

a fuse or insulated wire. Assuming the charge is to be fired electrically, the insulated wire 43 attached to the charge is threaded through the rod 30. This is done by first moving the locating rod into the body 10 until its end 32 abuts the wall 12. The bore 31 of the rod now communicates directly with the opening 14 in the inner end wall. The wire then can be fed through the marker plug without difficulty and a length of the wire can be left protruding from the outer end of the rod 30 for connection to the firing circuit. The locating rod is pulled outwardly to its fully extended position and the plug is reinserted in the hole.

By using the plug in this manner, the hole is tamped and both the explosive charge and the hole are protected. Also a clear warning is given that the area is charged and ready for firing. When firing takes place, the marker plugs obviously are lost or damaged but because of their inexpensive construction this is not too important.

The use of the plastic sleeve 36 is particularly important when ground temperatures are likely to be even close to freezing since a metal body 10 has been found to have a strong tendency to stick to the side walls of the hole. A sleeve 36 is fitted to the plug whenever the temperature is low or likely to become low at any time when the device is in use. Alternatively, the body 10 can be made of some suitable plastic material which obviates the need for using the sleeve 36 under the above-mentioned circumstances.

What I claim as my invention is:

1. A marker plug for a drill hole, said plug comprising an elongated body adapted to be inserted into the upper end of the drill hole, said elongated body being hollow and having a cylindrical side wall, an inner end member and an outer end member, a locating rod having a bore therethrough telescopically mounted in the elongated body in axial alignment therewith, said outer end member having an opening through which the locating rod extends, said inner end member having an aperture registering with the bore of the locating rod, said locating

rod normally retracted into the elongated body and providing access to said drill hole and being extendable therefrom to mark the location of said drill hole.

2. A marker plug as claimed in claim 1, said cylindrical side wall having a tapered portion adjacent the inner end member.

3. A marker plug as claimed in claim 1, said locating rod being frictionally supported in the opening of the outer end member and means on said rod for limiting movement of the locating rod outwardly of the elongated body.

4. A marker plug as claimed in claim 1, said cylindrical side wall having an external flange adjacent the outer end member, said external flange being adapted to halt movement of the elongated body inwardly of the drill hole.

5. A marker plug as claimed in claim 4, having a pair of lugs projecting laterally from said cylindrical side wall, said pair of lugs being spaced outwardly of the external flange.

6. A marker plug as claimed in claim 1, having a flexible sleeve enclosing the cylindrical side wall, said flexible sleeve having a rim portion contacted by the external flange.
